UNITED STATES PATENT OFFICE.

CHESTER H. FISHER, OF COUNCIL BLUFFS, IOWA.

HAMMER.

1,411,567.

Specification of Letters Patent.

Patented Apr. 4, 1922.

Application filed November 11, 1920. Serial No. 423,382.

To all whom it may concern:

Be it known that I, CHESTER H. FISHER, a citizen of the United States, residing at Council Bluffs, in the county of Pottawattamie and State of Iowa, have invented certain new and useful Improvements in Hammers, of which the following is a specification.

This invention relates to wood-working tools and more particularly to carpenters' hammers.

Briefly stated, this invention aims to provide a carpenter's hammer having a novel form of nail-set whereby a nail of any size may be detachably connected to the hammer preparatory to driving the nail into elevated work. That is to say, the improved hammer is capable of holding the nail while the same is being driven into the work a sufficient distance to hold the nail in position whereby further blows may be struck for driving the nail home.

A further object of the invention is to provide a carpenter's hammer having simple means whereby dirt and small bits of wood will be prevented from clogging the nail-set attachment.

A still further object of the invention is to provide a hammer having simple means whereby a nail may be removed from a piece of work.

The invention forming the subject-matter of this application aims also to provide a hammer having means whereby the same may be employed as a wrench.

A further object of the invention is to provide a hammer which is efficient in use, neat in appearance, and cheap to manufacture.

Other objects and advantages of the invention will be apparent during the course of the following description.

In the accompanying drawing forming a part of this application and in which like numerals are employed to designate like parts throughout the same:

Figure 1 is a fragmentary perspective of a hammer embodying the invention,

Fig. 2 is a detail sectional view through the same, and

Fig. 3 is a fragmentary side elevation of a hatchet having the improved nail-set.

In the drawing, wherein for the purpose of illustration is shown a preferred embodiment of the invention, the numeral 5 designates a hammer handle to which is connected

a hammer head designated by the numeral 6. The hammer head is, as usual, provided with an attaching shank 8 having a longitudinally extending opening 10 through which the forward portion of the handle is extended. A striking element 12 is formed integral with the attaching shank 8 and projects laterally from the same.

As illustrated in Fig. 1 of the drawings, one side face of the attaching shank 8 is provided with a pair of converging inwardly-extending retaining flanges 14 which cooperate with the adjacent portion of the shank in forming a socket 16 adapted for the reception of the head of a nail. The socket 16 opens out through the forward end of the shank 8 and slidably receives the head of a nail.

It frequently occurs that a nail is to be driven into a piece of work out of reach of both hands of the workman and, therefore, the workman is unable to hold the nail while starting the same. In such case, the nail may be connected to the hammer head by inserting the head of the nail in the socket 16. When thus inserted in the socket, the overhanging flanges 14 will securely hold the nail in position. The rear end of the hammer handle may now be grasped by the workman and by swinging the hammer head in the direction of the work, the nail will be driven into the work a sufficient distance to hold the same in position. Further blows may then be struck upon the nail by the striking element 12. When starting the nail, the hammer head may be given somewhat of a slanting blow so that the flanges 14 will be withdrawn from engagement with the nail. Further, as illustrated in Fig. 2, the bottom wall of the socket is inclined so that as the hammer head is given a slanting blow the flanges 14 will be effectively withdrawn from engagement with the head of the nail.

In other words, the socket 16 decreases in depth and width in the direction of its inner end so as to firmly grip the head of the nail as well as the shank of the same.

As illustrated in Fig. 1, a second pair of flanges 20 are formed on the side face of the attaching shank 8 and cooperate with the adjacent portion of the face of the shank in forming a socket 22 adapted for the reception of the head of a nail to be removed from a piece of work. With reference to Fig. 2, it will be observed that the socket 16 is in communication with the socket 22 so

that any dirt or small bits of wood which may lodge in the socket 16 may be readily passed off through the socket 22.

As illustrated in Fig. 1, the attaching shank 8 is provided with a longitudinally curved jaw 24 having a gradually reduced slot 26 adapted to receive the shanks of nails to be removed from pieces of work. The inner side of the longitudinally curved jaw and the adjacent side of the shank are provided with a plurality of transversely extending teeth 28 which may be engaged with such pieces of work as lengths of pipe and nuts. The jaw 24 and the adjacent face of the shank 8 therefore constitute a wrench somewhat similar in operation to an alligator wrench.

With reference to the foregoing description taken in connection with the accompanying drawing, it will be apparent that a hammer constructed in accordance with this invention is capable of a variety of uses. The hammer may be operated quite as freely as without the nail setting and removing means, since such means do not interfere with the use of the hammer in any way. The base walls of the sockets 16 and 22 which connect the opposed faces of the shank 8 and the flanges are parallel so as to permit nails of various sizes to be connected with the flanges 14 and 20.

In the form of the invention illustrated in Fig. 3, the hatchet head 30 is provided with a cutting blade 32 having the usual notch 34 adapted for the reception of nails when the nails are to be removed. The hatchet head 30 is formed in one side with flanges 36 which correspond to the flanges 14 which are employed for holding the nail in position when starting the latter. The hatchet head 30 is also provided with converging flanges 38 which correspond to the flanges 20 illustrated in Figs. 1 and 2.

One side of the attaching shank 40 of the head 30 and the adjacent edge of the blade 32 are formed with teeth 42 which provide a means whereby the head may be employed as a wrench for gripping pipes, etc.

The blade 32 is formed with a transverse opening or aperture 44 through which a wire may be passed when the head is used as a wire splicer. A similar hole is seen in the jaw 24 of the hammer head in Fig. 1.

Having thus described the invention, what is claimed as new is:

1. A hammer comprising a head, a pair of converging flanges formed on one side of said head and defining a socket opening out through the forward end of said head, said socket being adapted for the reception of nail heads, the bottom wall of said socket being inclined whereby the depth of the socket is gradually decreased in the direction of its inner end.

2. A hammer comprising a head having an attaching portion, a pair of flanges formed on one side of said attaching portion and defining a socket, the opposed edges of the flanges converging inwardly, and a second pair of flanges formed on said attaching portion and defining a second socket having communication with said first-named socket, the opposed edges of the second flanges diverging from the inner ends of the first flanges, said first and second named sockets opening out through opposite ends of the head.

3. A hammer comprising a head having an attaching portion, a pair of converging flanges formed on one side of said attaching portion and defining a socket, and a second pair of flanges formed on said attaching portion and defining a second socket having communication with said first-named socket, said first and second named sockets opening out through opposite ends of the head, the connecting base walls of said first and second named sockets being parallel.

4. The combination with a head having a blade and an attaching shank, one side of said shank and the adjacent edge of said blade being provided with teeth, of means formed on said head for gripping a nail, and a handle connected to said head.

In testimony whereof I affix my signature.

CHESTER H. FISHER. [L.S.]
